UNITED STATES PATENT OFFICE.

ARTHUR TREVOR DAWSON AND GEORGE THOMAS BUCKHAM, OF WESTMINSTER,
LONDON, ENGLAND, ASSIGNEES TO VICKERS LIMITED, OF WESTMINSTER,
LONDON, ENGLAND.

GUN-MOUNTING.

1,324,800.

Specification of Letters Patent. Patented Dec. 16, 1919.

Application filed September 6, 1916. Serial No. 118,633.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to Gun-Mountings, of which the following is a specification.

This invention relates to gun mountings of the kind capable of swinging about a horizontal or approximately horizontal axis which is transverse to the axis of the gun and situated a substantial distance from a transverse plane containing the training axis of the gun so that the gun and its mounting as a whole can be readily displaced in a downward direction from the firing position and housed, when not in use, within a chamber formed for example in the superstructure of a submarine or submersible boat. The type of mounting to which the invention relates is thus distinct from that type in which the mounting proper (that is to say the part with respect to which the gun moves in training) does not move with the gun during the displacement of the latter to and from its housed position.

According to the present invention the aforesaid horizontal axis is so situated in relation to the chamber and the mounting as a whole is so constructed that the latter during its downward housing displacement moves through an angle substantially less than a right-angle, this housing operation taking place without the necessity of inverting the gun.

In order that the said invention may be clearly understood and readily carried into effect, we will describe the same more fully with reference to the accompanying drawings, in which:

Figures 1 and 2 are sectional side elevations showing more or less diagrammatically two constructional forms of the invention.

Fig. 3 is a section taken approximately on the line 1, 1 of Fig. 2.

Figs. 4 and 5 are respectively a side sectional elevation and a sectional end elevation showing on an enlarged scale the manner in which the gear illustrated by Fig. 1 may be operated.

Fig. 6 is a view similar to Figs. 1 and 2

showing another constructional form of the invention.

Fig. 7 is a plan of Fig. 6 but with the gun and its mounting in the raised or firing position and

Fig. 8 is a section taken approximately on the line 2—2 of Fig. 6.

A is the gun and B is the base of the mounting. C is the chamber in the superstructure of a submarine boat, for the reception of the gun and its mounting when in the housed position. This chamber may be closed by a watertight door C'. D is the aforesaid pivot pin which passes through the forward part of the base B.

In the examples shown the gun mounting is of the cone type with worm and worm wheel training and elevating gears, the cone B' being built up of steel plate. This cone moves with the gun in training and a ball or roller path may be interposed between its lower part and the base B of the mounting.

Referring to Figs. 1, 4 and 5, the gear for raising and lowering the mounting comprises two screw threaded shafts E, E each engaging with a nut E' pivotally mounted at e' on the rear part of the base B. Each shaft is carried by a bracket e pivoted to the stationary structure and is operated through suitable shafts and bevel or other gearing from the interior of the boat. In Figs. 2 and 3 the screw threaded shafts are replaced by two fixed racks E², E³ with which mesh pinions e², e³ operated through worm gearing from a shaft B^x. This shaft may be driven by bevel wheels from the pivot D which in this case constitutes a shaft actuated from the interior of the boat by bevel gearing and a shaft as will be readily understood by reference to Fig. 5.

Referring to Figs. 4 and 5 it will be seen that the two screw threaded shafts E, E are arranged one at each side of the base B. In Fig. 4 the mounting is assumed to be in its lowered position and in Fig. 5 in its raised position. F (Fig. 5) is an electric or other motor situated within the submarine boat and operating upon the shafts E, E simultaneously through the gearing shown. Suitable means operated by a handle f' are provided for reversing the direction of movement of the shafts simultaneously without necessitating the reversal of the motor. For this purpose a rod f^x operated by the handle f' is connected to

sleeves f , f each slidably keyed to the motor shaft F^x so that one or the other of two bevel pinions carried by each sleeve can be brought into gear with a bevel wheel on a shaft F^o operating the screw threaded shaft E .

The weight of the mounting about the pivot pin D may be balanced by an air or spring recuperator. In this case no gearing would be required for raising or lowering the mounting, the whole mass being lifted directly by hand.

In Figs. 6, 7 and 8 the mounting is operated directly instead of through gearing by a pneumatic or hydraulic press or cylinder F' whose ram or piston rod F^2 is connected to an arm or bracket B^2 carried by the base of the mounting. This press or cylinder also acts as a balancing recuperator, as much as possible of the unbalanced weight of the mounting being balanced, the pressure of the air or liquid being increased or decreased as required, for raising or lowering the mounting.

It is to be understood that any other suitable form of power or hand operated gear may be employed for raising and lowering the mounting, and that means would be provided for locking the mounting in either of its aforesaid positions.

Although we have described the pivot pin D as being situated in front of a transverse plane containing the training axis of the gun, it is to be understood that it may be situated to the rear of the said plane, the mounting then swinging in a forward direction during the housing operation.

What we claim and desire to secure by Letters Patent of the United States is:—

1. The combination with the training and the non-training portions of a gun mounting, of a chamber in which the gun and mounting are adapted to be housed, and means for pivoting the non-training portion of the mounting so that during the housing displacement of the mounting as a

whole it moves through an angle substantially less than a right angle without the necessity of inverting the gun.

2. The combination with the training and non-training portions of a gun mounting, of a chamber in which the gun and mounting are adapted to be housed and a pivot for said non-training portion of the mounting, this pivot being arranged a substantial distance from a transverse plane containing the training axis of the gun, the mounting as a whole moving about this pivot during the housing of the gun through an angle substantially less than a right angle without the necessity of inverting the gun.

3. The combination with the training and the non-training portions of a gun mounting, of a chamber in which the gun and mounting are adapted to be housed, and a pivot for said non-training portion of the mounting, this pivot being arranged a substantial distance in front of a transverse plane containing the training axis of the gun, the mounting as a whole moving about this pivot during the housing of the gun through an angle substantially less than a right angle without the necessity of inverting the gun.

4. The combination with the training and the non-training portions of a gun mounting, of a chamber in which the gun and mounting are adapted to be housed, means for pivoting the non-training portion of the mounting so that during the housing displacement of the mounting as a whole it moves through an angle substantially less than a right angle without the necessity of inverting the gun and a pressure fluid motor for displacing the mounting to and from its housing position.

ARTHUR TREVOR DAWSON.
GEORGE THOMAS BUCKHAM.
